UNITED STATES PATENT OFFICE.

SOLOMON D. WOLLISON, OF PITTSFIELD, MASSACHUSETTS.

APPARATUS FOR THROWING PROJECTILES.

Specification forming part of Letters Patent No. 39,858, dated September 8, 1863; antedated January 31, 1863.

To all whom it may concern:

Be it known that I, SOLOMON D. WOLLISON, of Pittsfield, in the county of Berkshire and State of Massachusetts, have invented a certain new and useful Improvement in the Art of Projecting Torpedoes and other Similar Projectiles; and I do hereby declare the following to be a full, clear, and exact description of the same, reference being had to the annexed drawing, making a part of this specification.

The object of my invention is to project torpedoes and other similar fulminating projectiles with steam or other mechanical power with great velocity and certainty of direction from any point against any object or vessel which it may be desirable to destroy or remove—such as the works or ships of an enemy, obstructions in channels, and the like. This object I propose to accomplish by fixing the torpedo on the end of an elongating projector so made as to cause the torpedo to travel through a long distance and at a high velocity, while the motive power moves through a short space and with a comparatively slow motion.

The drawing represents an apparatus capable of fulfilling these objects. It consists of a series of bars, H H, joined at their ends and centers so as to form what I term a "lattice projector." The manner of joining the bars together so as to form this jointed lattice-work is well known, and therefore no special description here is necessary.

The drawing shows a projector applied to a platform, A, in which angular grooves *a b* are cut, in which pins *v v* are made to work to hold the lattice-work to direct and give effect to the action of the rod B, which acts against the center joint of the lower section of the projector and to which the power is applied.

The torpedo is fixed to the projector by means of a socket or other similar device arranged on the out end of said projector in the manner shown.

The drawing represents a projector consisting of seven sections, so that the torpedo travels fourteen times as far as the rod B, or nearly so, for the rod B in operating the projector travels but little more than half the length of one of the sections, so that the distance the torpedo will be thrown will depend upon the number of sections composing the projector, and not upon the distance traveled by the moving power.

There are a variety of ways in which the projector can be arranged on the platform. Thus, the center of the lower section might be fixed to the platform and the power applied to the two lower ends, and the effect would be the same.

The apparatus may be fixed in the hull of a ship in water-tight compartments, or on the deck, or on a raft, on land, or on or in any apparatus which will support it and in which it can be operated; and the power may be applied in any convenient way.

The torpedo should be made buoyant enough to float and to support the end of the projector when thrown out, to keep it from deflecting.

Having now described my improvement in the art of projecting torpedoes and similar fulminating projectiles, I claim and desire to secure by Letters Patent—

The combination of a torpedo or similar projectile with the elongating projector, for the purpose of projecting the same as described, for the purpose specified.

In witness that the above is a full, clear, and exact description of my improvement in the art of projecting submarine torpedoes and similar projectiles, I have hereunto set my hand this 12th day of June, 1862, in presence of the subscribers.

S. D. WOLLISON.
